United States Patent Office.

LEWIS ELLIOTT, JR., OF NEW HAVEN, CONNECTICUT, ASSIGNOR TO L. CANDEE & CO., OF SAME PLACE.

Letters Patent No. 76,731, dated April 14, 1868.

IMPROVEMENT IN OVER-SHOES.

The Schedule referred to in these Letters Patent and making part of the same.

TO ALL WHOM IT MAY CONCERN:

Be it known that I, LEWIS ELLIOTT, Jr., of New Haven, in the county of New Haven, and State of Connecticut, have invented a new Improvement in Over-Shoes; and I do hereby declare the following, when taken in connection with the accompanying drawings, and the letters of reference marked thereon, to be a full, clear, and exact description of the same, and which said drawings constitute part of this specification, and represent, in—

Figure 1, a perspective view, and in

Figure 2 diagram of the cloth upper.

This invention relates to an improvement in the common rubber shoe, the object being to give to the shoe the appearance of a rubber foxing and fabricated upper, and so as to possess the advantages of that class of shoes, but produced at less expense; and my invention consists in applying to the common rubber shoe, while in a plastic state, a partial upper cut from any suitable fabricated material, the said upper being placed upon the shoe so as to show a foxing of rubber, and secured to the shoe and completed by the process of vulcanization.

Heretofore, in the construction of this class of shoes, a foxing has been applied to a fabricated upper, the upper extending down inside the rubber to the sole of the shoe, and the edge bound by a narrow coating of India rubber. This construction requires a greater amount of labor and more expense of material than by my improvement.

To enable others to construct my improvement, I will proceed to describe the same as illustrated in the accompanying drawings.

The shoe, as seen in fig. 1, is first formed in the usual manner of forming entire rubber shoes, that is to say, with an entire upper of India rubber. From a suitable fabric I cut an upper, A, nearly as denoted in fig. 2; then, while the shoe is in a plastic state, and upon the last, I place the fabric thus cut, as seen in fig. 1, preparing it so as to unite with the plastic upper; then submit the whole to the process of vulcanization, which secures the upper to the shoe, and thus I produce a shoe, possessing fully all the qualities of the cloth and rubber shoe heretofore manufactured, and this by the use of much less of the fabricated material than heretofore used.

The upper edge should be set so as to show a narrow edge of rubber around the top, as seen in fig. 1, and this edge being corded, or thicker than the other portions of the rubber, projects over and protects the upper edge of the cloth.

I do not wish to be understood as broadly claiming an over-shoe, the foxing of which is of rubber, and the upper composed of two fabrics, cemented together and attached to the foxing, as such, I am aware, is common and well known.

Having thus fully described my invention, what I claim as new and useful, and desire to secure by Letters Patent, is—

An over-shoe, formed from India rubber in the usual manner, and provided with a fabricated upper, A, when the said upper is applied thereto in the manner herein set forth.

LEWIS ELLIOTT, JR.
